UNITED STATES PATENT OFFICE.

ESMOND M. SMITH, OF CLEVELAND, OHIO, ASSIGNOR TO THE MULTI-LUX ILLUMINATING COMPANY, OF CLEVELAND, OHIO, A CORPORATION.

LIGHTING-FIXTURE.

1,106,685.

Specification of Letters Patent. Patented Aug. 11, 1914.

Application filed February 21, 1914. Serial No. 820,109.

To all whom it may concern:

Be it known that I, ESMOND M. SMITH, citizen of the United States, residing at Cleveland, in the county of Cuyahoga and State of Ohio, have invented certain new and useful Improvements in Lighting-Fixtures, of which the following is a specification.

This invention relates to lighting fixtures, and the invention comprises a simple and practical organization of parts especially designed for electric lamps and to give indirect or semi-direct lighting effects, all substantially as herein shown and described and more particularly pointed out in the claims.

15 In the accompanying drawings, Figure 1 is a plan view of the fixture, and Fig. 2 is a vertical sectional view thereof. Fig. 3 is a side view, and Fig. 4 a sectional view of the inverted shade suspended in an inclined position. Figs. 5 and 6 are perspective views of a link and a link coupling. Fig. 7 is a perspective view of the detachable cap for the bottom of the shade or reflector.

The device comprises a bell-shaped sleeve or member 2 secured to a pipe or other suitable support by a nut 3, and an electric lamp socket 4 is affixed to the pipe and enclosed within and apart from the member 2. The depending flaring rim 5 has key-openings 6, three or more, which are adapted to receive the ball ends 7 of a set of rigid links or rods 8 having open hooks or eyes 9 at their outer extremities wherewith a hinged and detachable connection may be made with the separate coupling studs 10 which project through openings 11 in the flaring rim of the bowl or inverted shade or reflector 12. This shade may be of any suitable shape or design. Each stud 10 has an opening at one end and a head at its other end and the stem adjacent the head is rounded to permit free rotation of the stud in the round opening 11 in the wall of the shade. The bowl or shade is generally made of glass, although other material, opaque or translucent, may be used. Rotatability of the stud and a perfectly free-turning connection for the link 8 is of advantage, especially when the ball end of any one of the said links is detached from the member 2 and the shade is suspended in an inclined position from the other links as shown in Figs. 3 and 4. It is possible to lower the shade at three different radial points of the fixture and the links are easily disconnected

from member 2 by lifting the ball ends thereof out of the narrow portions of the key-slots, but otherwise the weight of the shade will hold the said ends of the links securely in place in said key-slots. The ball ends of the links are also curved or bent at an angle to the main body of the stem to assure this locking union of the parts, especially when the shade is dropped or lowered and hangs by gravity at the center of the fixture. The bent ends also accommodate the turning of the links in the slots and relieve the member 2 of twisting strains, and the free link connection at the studs, and the rotatability of the studs in the shade also provides accommodating movements which relieve all bind and strain in this organization of parts. The shade may be entirely disconnected from member 2 by removing all of the links from the key-slots, and it is also a simple matter to unhook each link from its stud and to remove the stud from its opening in the shade providing that the link is manipulated properly for this purpose. The fixture is easily assembled or separated, and also tilted to give access to the lamp 14 and socket 4 as well as to the interior of the shade when it is necessary to clean the same. The bottom of the shade is shown as having a clean-out opening 15 and a metal cap 16 closes this opening but is removably supported from the annular bead 17 by the spring fingers 18.

What I claim is:

1. A lighting fixture comprising a shade, a slotted member, and rods hinged to said shade having locking ends detachably engaged with said member.

2. A lighting fixture comprising an inverted shade having a rim with openings, a central member having openings, and rods and coupling members removably seated within the respective openings in the said member and shade.

3. A lighting fixture comprising a shade having a rim provided with openings, studs seated within said openings, rods having hinged engagement with said studs and provided with ball ends, and a central member having key-openings for the ball ends of said rods.

4. A lighting fixture comprising a sleeve member having key-openings, rods having bent ends and enlargements thereat in detachable seating engagement with said open-

ings, studs hinged to the outer ends of said rods, and a shade having openings in which said studs are free to turn.

5. A lighting fixture comprising a lamp socket support, a sleeve member having key openings, rods having bent inner ends provided with ball extremities and the outer ends of said rods having eyes, swivel studs

detachably engaged with said rod eyes, and a shade having openings to seat said studs.

In testimony whereof I affix my signature in presence of two witnesses.

ESMOND M. SMITH.
